(57) **CLAIM**

The ornamental design for a notebook computer housing, as shown and described.

DESCRIPTION

FIG. 1 is a perspective view of a notebook computer housing shown in a closed configuration according to our design; FIG. 2 is a top view thereof; FIG. 3 is a bottom view thereof; FIG. 4 is a front side view thereof; FIG. 5 is a back side view thereof; FIG. 6 is a right side view thereof; and, FIG. 7 is a left side view thereof.

Broken lines are environmental only and form no part of the claimed design. The pairs of closely adjacent, spaced jagged broken lines in the drawings form no part of the claimed design and the portions between such pairs of jagged broken lines are broken away to disclose indeterminate length. Portions of the design that may be visible between the jagged lines have been removed for clarity.
